MECHANISM FOR TRANSFERRING FREIGHT

Benjamin F. Fitch, Greenwich, Conn., and Ragnar A. Norbom, New York, N. Y., assignors to National Fitch Corporation, New York, N. Y., a corporation of Delaware

Application October 17, 1940, Serial No. 361,566

30 Claims. (Cl. 214—83)

This invention relates to a system of transferring freight in demountable containers which may be transported on highway trucks or railway cars and shifted from one to the other in a combined truck haul and rail haul operation. The primary object of the invention is to provide effective mechanism carried by the highway truck and operative to shift the container on the truck to an adjacent vehicle or to pull the container from such vehicle onto the truck.

For effecting the body-transferring operation, we provide a shiftable carriage mounted on the truck and a propelling chain partly on the carriage and partly engaging a sprocket carried directly by the truck, and a push-and-pull bar adapted to connect the chain with the container. By the operation of the chain, we may shift the carriage partially beyond the edge of the truck, where we are able to attach the push-and-pull bar to the chain while the container is in transporting position entirely over the truck. Then by operating the carriage or chain or both together, we may shift the container not only off of the truck but beyond it on to a freight car or other adjacent vehicle. By a reverse operation we may draw the container from the railway car or other vehicle into position, directly over the frame of the truck, suitable for transportation.

Our shiftable carriage transferring mechanism is well adapted for mounting transversely on the highway truck, which may then be placed alongside of a railway car or other vehicle to or from which the body is to be transferred. In this case the highway truck preferably has two parallel laterally movable carriages, each carrying its own endless chain, and there are two push-and-pull bars to connect the chains with the container.

The railway car and highway vehicle are provided with registering transverse channels adapted to receive skid rails on the bottom of the container, and the highway vehicle has a pair of bridges which may be connected to the side of the car in registration with the channels of the car and truck. This makes a continuous runway from the car to the truck and enables the container to be pulled off of the car or pushed onto it while the container is maintained in parallelism with the side of the truck.

Our invention may also be employed to carry the container from the highway truck equipped with our transferring mechanism to an adjacent highway truck equipped only with skid rail channels and means for attaching the bridges of that side of the equipped truck. Where the truck is

designed for shifting the body laterally it has bridges at each side, and thus may be readily attached at either side to a railway car or, for instance, on one side to a railway car and on the other side to another highway truck.

The shiftable carriages on such installation may be caused by the operation of the chain to shift to either side of the highway truck, until the limit of movement is reached (provided by inter-engaging stops on the truck and carriage) or until the free end of the carriage abuts the side of the railway car or the side of the additional truck, as the case may be, and then the chain traveling relative to the carriage may move the push-and-pull bar to effect the transfer as hereinafter explained.

In addition to providing a combined truck and railway haul system, the mechanism of this invention is adapted for coaction with branch truck lines, where the traffic is not sufficient to warrant the use of trucks equipped with transferring mechanism. Such branch trucks may bring the loaded bodies to a clearance region where they may be unloaded onto the truck equipped with transfer mechanism by the power of the latter truck, and conveyed by such latter truck to the rail head, or the non-equipped trucks may take the bodies direct to the rail heads, and the equipped truck there used as an intermediate transfer device for carrying the body from the non-equipped truck across the equipped truck to the railway car, or vice versa.

Our invention is illustrated in the drawings hereof, which show an approved embodiment of the transfer mechanism, and also by diagrams of operation, all of which is about to be explained.

In the drawings, Fig. 1 is a plan of a highway truck (of the tractor, trailer type) equipped with our transfer mechanism, this view showing also a portion of an adjacent railway car and a container on the car connected with the transfer mechanism on the truck; Fig. 2 is an end view of such a truck and railway car, as shown in Fig. 1, and showing also a local truck adapted to receive or discharge the container by the mechanism of the equipped truck, shown centrally in this figure; Fig. 3 is a vertical section through the truck equipped with our transfer mechanism; Fig. 4 is a horizontal section through a portion of one of the shiftable carriages of the truck, as indicated by the line 4—4 on Fig. 3; Fig. 5 is a detail in elevation, showing a portion of the shiftable carriage and chain, the latter coupled to the push-and-pull bar; Fig. 6 is a vertical section through the carriage chain and push-and-pull

bar connection, as indicated by the line 6—6 on Fig. 5; Fig. 7 is a vertical section through the chain-driving mechanism, as indicated by the line 7—7 in Fig. 3; Fig. 8 is a sectional end elevation illustrating the carriage in extended position suitable for starting the movement from the flat car, the position of this section being indicated by the line 8—8 on Fig. 1; Fig. 9 is a detail in end elevation, showing the attachment of any of the bridges to the highway truck and at the far end to the railway car, the position being indicated by the line 9—9 on Fig. 1.

The remaining figures are diagrams, in the nature of end elevations, illustrating the position of the parts during the transfer operation, Figs. 10, 11 and 12 relating to the transfer of the container from the flat car to the truck; Figs. 13, 14 and 15 from the truck to the flat car; Figs. 16, 17 and 18, from a truck equipped with our propelling mechanism to an adjacent local non-equipped truck. More particularly, Fig. 10 indicates the position of the parts at the beginning of the operation of drawing the body from the flat car by a movement of the chain on the carriage; Fig. 11 indicates the position of the parts at the completion of such movement of the chain, where the movement of the carriage with the chain is about to begin; Fig. 12 indicates the position after the carriage and chain have moved as a unit far enough to bring the body directly over the truck in position for transportation; Fig. 13 is a view of the parts in a position very similar to Fig. 12, but with the connections ready for starting the movement from the truck to the flat car; Fig. 14 is a view illustrating the end of this movement of the chain; Fig. 15 is a view indicating the subsequent movement of the carriage and chain as a unit to complete the shoving of the body onto the flat car; Fig. 16 indicates the initial position of the carriage in shoving the body by means of the chain from transporting position on the truck onto the local truck at the left thereof; Fig. 17 indicates the stage at the completion of such chain movement of the body; Fig. 18 indicates the final position where the shifting onto the local truck has been completed by moving the carriage and the chain as a unit.

As shown in Figs. 1 and 2, A indicates a highway truck, which may be of the tractor-trailer type, and is equipped with our transfer mechanism; B indicates a railway flat car; C a local truck; D a container adapted to be carried on any of the three vehicles A, B or C. Each vehicle is equipped on its upper face with transverse channels *a*, *b*, and *c*, respectively, which may receive skid rails *d* on the under side of the container. The main frame of the equipped truck is provided at each side with a pair of bridges *E* which may extend various distances from the side of the truck and which are adapted for attachment at their far ends to the adjacent vehicle. The railway car is equipped at its side with folding wings *F* adapted for attachment at the end of the bridge. Likewise, the local truck C is provided with similar folding wings *F*—1.

The attaching devices enable the bridges at either side of the main truck to be attached either to a railway car or to a local truck, or the three vehicles may be thus connected together, as shown in Fig. 2, with their channels all in registration, the space between such channels being occupied by the bridges *E*, which form guides for the skid rails and supports for part of the weight of the container in passing from one vehicle to the other.

The propelling mechanisms on the main truck, 75

about to be described, are connected with the container D by push-and-pull bars *G*, which are attached at one end to the sides of the container near its base and at the other end to the laterally traveling propelling mechanisms on the highway truck. This will be best understood after we have described the propelling mechanism itself.

Referring now to Figs. 3 to 8 inclusive, the main 10 sills of the chassis on the truck A are shown as a pair of outwardly facing channel beams *H*. On top of these beams, extending cross-wise thereof, over suitable pads *I*, are a pair of transverse angle beams having vertical flanges *J* and horizontal outwardly facing flanges *K*. The flanges *J* are spaced apart to house the carriage and guide it by their inner faces. The angle beams are connected with the longitudinal chassis beams *H* by gussets *L* welded to the vertical flanges *J*, to the horizontal flanges *K*, and to the longitudinal beams. At their free ends the flanges *J* are tied together by cross rods *M* mounted in bracket plates *N* welded to the sides of the flanges *J* and these rods carry rollers *O* between the brackets, making a convenient support for the carriage, as will later be more fully described.

It will be understood that the construction just 30 described is duplicated so that it occurs at two spaced regions in the truck. The gussets *L* may lead continuously from one transverse housing to the other and beyond the two housings brace members may lead to the ends of the truck platform.

In the two housings are two chain-carrying arms or carriages, which will now be described. Each carriage or arm is composed of a hollow substantially square beam *P*, Fig. 7, to the opposite vertical faces of which are welded reinforcing plates *Q*. These plates extend above and below the hollow beam and provide, in effect, channels along the top and bottom of the beam. On the upper face of the hollow beam is a substantially flat supporting bar *R* which forms a guide 40 for the upper reach of the endless chain carried by the carriage. This chain extends around the end of the carriage and beneath it where, being itself supported, it supports the carriage.

The chain is composed of overlapping side links 50 arranged in two spaced series, transverse pins *S* pivoting the overlapping links together and connecting the two series to each other in spaced relation and rollers *T* on the pins between the innermost links. This chain lies in a vertical course, the upper reach horizontal with the rollers *T* resting or rolling on the track bar *R*.

The chain *S* passes about a pair of sprocket wheels *U*, each of which is journaled in a yoke *V*, which is slidably mounted in the guides 25 and 26 carried by the end castings *W* which form a continuation of the plates *Q* of the carriage. The end of the yoke *V* is abutted by a screw *X* which is threaded in a block *Y* secured in the end of the hollow beam *P*. The angular heads of the screws *X* are accessible through openings *Z* in the carriage, thus enabling the yokes and sprocket wheels to be shoved outwardly to provide a proper tension on the chain.

The carriages are adapted to be projected to either side of the truck by operation of the chain, as later described. When so projected, the carriage is adapted to assume an angle below the horizontal, so that it may more surely abut an adjacent vehicle below its upper edge, for a purpose to be later described. To this end, the cast-

ings 24 are provided with depending projections 24a, at the ends of the carriage, which rest upon the rollers 19 when the carriage is in the central traveling position on the truck, as shown in Fig. 3. When the carriage is moved outwardly, however, the leading projection 24a rides down off the roller and the carriage is henceforth supported at an angle, resting on the chain links 30 at the idler sprockets 53 and 55 and at the roller 19, as illustrated in Figs. 7 and 8.

The projections 24a, as illustrated in Figs. 5 and 6, comprise vertical webs 24b, at either side of the casting, having outwardly extending flanges at their ends and bottoms. Hook-shaped pockets 95 are thus formed, the purpose of which will be later described.

The chain is adapted to be engaged by the push-and-pull bar, the other end of which is attached to the container, and, as hereinafter explained, the chain may move relative to the carriage or move as a unit with the carriage and in either case may effect the shifting of the container through the push-and-pull bar.

At the center of the truck is a shaft 50 carrying a sprocket wheel 51 and on opposite sides of this shaft are shafts 52 and 54 carrying sprocket wheels 53 and 55 respectively. The chain 30 is endless, its lower reach passing beneath the sprocket 51 and in engagement with it, and on each side thereof passing over the sprockets 53 and 55 and in engagement with them. All of the shafts 50, 52 and 54 are rotatably mounted in the chassis of the truck, being preferably journalled in bearings in a housing 56, welded to the transverse beams 12.

The sprocket 51 is preferably the driving sprocket for the chain and is tight on its shaft 50. Tight also on this shaft is a spur gear 57 which meshes with a pinion 58 tight on the shaft 54 which loosely carries the sprocket wheel 55. The shaft 54 is the main driving shaft of the gearing, being connected through suitable couplings and reduction gearing 60 to a driving motor 61 on the truck, as indicated in Fig. 1. The reduction gearing includes a worm and worm wheel, which renders the chain self-locking in any position.

When the motor 61 is operated, the driven shafts 54 rotate the corresponding pinions 58 and through them gears 57, and thus rotate the driving sprockets 51 to move the chains. Now, if the carriage is held stationary the propelled chain will travel about the two sprockets 40. If, however, the carriage is free to move it is possible for the chain to pull the carriage so that the chain and carriage shift as a unit. The operation of our system, in the embodiment herein illustrated, depends on this characteristic of the chain sometimes moving relative to the carriage and sometimes moving as a unit with the carriage. This will be clear when we describe the operation after completing the description of the structure.

The push-and-pull bar G, which may be formed according to Patent No. 2,087,249, issued July 20, 1937, to Benjamin F. Fitch, has at its free end a flattened head g which may pass through a vertical slot in the side of the container, if the push-and-pull bar is held so that the head is at right angles to the position shown in Figs. 2 and 8, and then when the bar is turned into the position shown the head g lies behind the walls of the slot, thus anchoring the bar at that end. At its other end the bar G has a downwardly-facing curved portion 70 at the opposite sides of which

are pivoted a pair of links 71. Below the bar these links carry a block 72 having downwardly facing teeth which are adapted to extend into the spaces between the rollers 32 of the chain.

The transverse pin 75 by which the links 71 are pivoted to the block 72 also carries a pair of downwardly extending arms 76 which have heads 77 at their lower ends adapted to engage in hook-shaped recesses 29 in the castings 24 of the carriages. As shown, the two bars 76 extend downwardly on opposite sides of the block 72 and the heads 77 occupy the hooked recesses 29, as shown in Figs. 5 and 6, and in this position the chain, through the block 72 and arms 76, is attached for one direction of movement to the carriage 20; that is to say, if the upper reach of the chain moves to the right in Fig. 5 it must carry the carriage with it, as hereinafter explained in connection with the diagrams.

We have referred to the bridges E connecting the truck with the adjacent vehicle. As shown, these bridges are slidable, when not in use, into transverse housings a-2 carried by the truck frame. When in use they extend various

distances out of the housings, as shown in Fig. 9, and are pivotally locked in such position by suitable latches 81 on the sides of the housing. The construction may be such that each bridge has a row of recesses 80 on its opposite sides, any of which may be occupied by a ball 81, forced toward the bridge by a camming device 82 on the side of the housing. When the truck is brought into position at the side of the railway car or the other vehicle, the bridges are drawn out towards such other vehicle and the free ends are attached thereto by the wings F or F-1, and then the ball locks 81 applied to force the opposed balls into selected opposed recesses to lock the bridges in position on the truck.

In considering the operation of our transfer system, suppose a truck arrives empty adjacent a flat car and it is desired to draw a container from the car onto the truck. The first operation, after the bridges are attached, is to operate the driving sprocket 51 in the counter-clockwise direction, as viewed in Figs. 3 and 10 to 18. This pulls on the left hand portion of the lower reach of the chain and thus pulls the carriage toward the right. The carriage continues to move in this direction until it is stopped either by its hooked end engaging the stop on the truck or more usually by the end of the carriage abutting the side of the car B, as shown in Fig. 10. The end of the carriage is formed with a yielding bumper strip 90 which may, for instance, be of leather, which cushions the blow as the carriage strikes the car.

When the carriage has been thus projected until stopped, the power is turned off from the motor. Then the push-and-pull bar G is attached to the container and the free end of the bar is attached to the upper reach of the chain by the toothed block of the push-and-pull bar with the arms 76 extending in the direction of intended travel. Now, the power is turned on in the same direction as before and this pulls the lower reach of the chain toward the right. As the carriage can move no further toward the right, the pull on the lower reach of the chain is transmitted to movement of the upper reach toward the left relative to the carriage and this pulls the container along over the chain until the pull bar is near the end of its possible travel.

When the pull bar reaches the end of the travel, the heads 77, which have been riding

on the top of the side plates 21 of the carriage, come opposite the openings 29 and drop into such openings, as shown in Fig. 5. This is the position of the parts in Fig. 11. Now if the motor be reversed, so that the driving sprocket 51 is moved in a clockwise direction as viewed in the diagrams, this pulls on the right hand portion of the lower reach of the chain and since the chain cannot now move relative to the carriage, because of the engagement of the heads 77, the carriage is drawn to the left, carrying with it the container, so that the parts come into the position shown in Fig. 12 where the container is centrally positioned over the truck.

When the container comes into central position on the truck, the push-and-pull bar is removed from the carriage chain and container, and it is only necessary to operate the driving sprocket 51 in the counter-clockwise direction to pull the carriage back to original mid-position. The truck is then ready for transportation movement after the bridges have been disconnected from the car and the container suitably locked on the truck. This is the position illustrated in Fig. 3.

When a truck arrives loaded adjacent the flat car, the first operation is to rotate the driving sprocket 51 in the clockwise direction, thus pulling the carriage out to the left, as shown in Fig. 13. Then the push-and-pull bar is attached to the chain, with the arms 76 toward the right, as shown in Fig. 13, and then the movement of the driving sprocket 51 in the clockwise direction is continued. This tends to pull the carriage farther toward the left, but it cannot move in that direction by reason of the engagement of the hooked lower end 95 of the carriage with fixed stop pins 96 projecting inwardly from the vertical flanges 12 on the truck. Accordingly, the chain travels on the carriage, and the upper reach of the chain moving toward the right carries the parts into the position shown in Fig. 14, where the container has been moved part-way onto the flat car, and the links 76 have just brought the heads 77 over the recesses 29 at the right hand end of the carriage. The heads thereupon drop into these recesses, as indicated in Fig. 14.

Now the direction of rotation is changed so that the main sprocket 51 rotates in the counter-clockwise direction. This pulls on the left hand portion of the lower reach of the chain and, as the upper reach is anchored by the parts 76, the whole carriage must move toward the right. This movement continues until the container is in proper position on the flat car, as shown in Fig. 15, after which the push-and-pull bar is detached and the motor operated in the reverse direction to rotate the main sprocket 51 in the clockwise direction, thus pulling the carriage back to mid-position.

Suppose the truck, carrying a loaded body arrives adjacent a branch line highway truck adapted to receive the body but not equipped with transfer mechanism, as indicated at C in Figs. 2 and 16. In this case the main sprocket 51 is rotated in the counter-clockwise direction, thus pulling the carriage toward the right as far as it will go, which may result when the end of the carriage abuts the side of the adjacent flat car, as shown in Fig. 16, or if there is no flat car present when the hook 95 at the rear end of the carriage engages the stationary stop 96 on the truck frame. When the carriage is stationary, in this extended position the push-and-pull bar is applied, with arms 76 toward the left,

and the motor is rotated in the same direction as before, to carry the upper reach of the chain toward the left, thus shoving the container part-way onto the branch line truck, as shown in Fig. 17.

When the end of the push-and-pull bar, which engages the chain, reaches the left hand end of its movement, the heads 77 drop into the openings 29 of the carriage and lock the push-and-pull bar and chain both to the carriage. Now the direction of rotation of the motor is changed, so that the sprocket rotates in a clockwise direction which pulls on the right hand portion of the lower reach of the chain. The upper reach being anchored, the result is that the whole carriage moves to the left shoving the container ahead of it. This movement continues until the container is in proper position on the branch line truck, as shown in Fig. 18, whereupon the push-and-pull bar is removed and the carriage restored to normal position.

It will be seen that our mechanism is comparatively simple in construction, comprising essentially two endless propelling chains, two carriages on which they are mounted and two sets of driving sprockets and gearing connecting them to an operating motor. The weight of each carriage is taken directly by links of the lower reaches of the corresponding chains and it requires less force to pull the carriage by the chain than it would to propel the chain with the carriage remaining stationary. Accordingly, even though there is no load on the carriage the initial operation of the motor, though it acts through the chain, is to shove the carriage in one direction to the other as desired to enable the attachment of the push-and-pull bar. In other words, if the carriage is free to move it will simply be carried along on the chain, resting upon its lower reach, as illustrated in Fig. 7.

If the push-and-pull bar is attached to the chain alone (as when the carriage abuts the side of the car carrying the container) then the operation of the chain in the direction to press the carriage against the flat car can only result in the top reach of the chain traveling away from the flat car so that it draws the container with it. Then when the anchored end of the push-and-pull bar reaches the end of the course which the chain is able to move it independently of the carriage, it becomes automatically attached to the carriage, and then the application of power in proper direction to the chain moves the carriage and chain as a unit to continue the movement of the container.

It will be seen that all movements desired in the shifting of the container are effected from a single motor merely by changing its direction of rotation at the proper time. So far as the operator is concerned all he need do is turn on the motor, then stop it and attach the push-and-pull bars and then turn on the motor for a time and then change its direction of rotation, then stop the motor and detach the push-and-pull bars when the container is in transporting position, and finally restore the carriage to normal position.

When the highway truck is about to travel, the container is locked to the truck by some suitable mechanism not shown, and the carriages may be locked so that they cannot inadvertently shift to either side of the truck. This lateral locking may be effected by suitable inter-engaging mechanism between the carriages and truck, or by inter-locking the carriages to their chains, be-

cause the chains are self-locked due to the worm and worm wheel in the reduction gearing between the motor and driving sprocket. A convenient means for locking the chain is a suitable clutch or dog to engage one of the sprockets on the carriage. Such a device might also be used to insure the carriage moving laterally to its limit when the chain sprocket is rotated, if there should be any binding of the carriage in its housing, due to accidental distortion of the parts or an abnormal accumulation of rust or dirt during a period of disuse.

The bridges for attaching the truck to the railway car preferably have a loose play connection in the attachment to compensate for difference in spacing between the car and truck. This loose play connection leaves the edge of the truck adjacent the car free to move up and down on the truck springs as the proportion of the weight of the load at such edge varies in shifting the container. Now with our improved transfer mechanism the engagement of the carriages with the side of the car has the additional advantage of forming a steady connection between the truck and car reducing the tipping tendency during the transfer from the car to the truck.

We claim:

1. The combination of a vehicle, a carriage bodily movable thereon beyond the edge of the vehicle, an endless chain extending around the carriage lengthwise thereof in such manner that the carriage rests on the reach of the chain beneath it so that the travel of the chain may move the carriage, a driving sprocket on the vehicle engaging the chain, and means to connect a container with the chain.

2. The combination of a vehicle, equipped with upwardly facing guides, a container having means on its base adapted to coact with said guides, a laterally shiftable carriage on the vehicle, an endless chain looping around the carriage lengthwise thereof and movable relative to the carriage, the carriage being so supported that it may be shifted lengthwise by a pull on the under reach of the chain, means to connect the chain with the carriage to prevent independent movement, means on the vehicle for driving the chain, and means to connect the chain with the container.

3. The combination of a highway truck, a transversely extending guideway thereon, a carriage mounted in the guideway and movable to either side of the truck, an endless chain in the guideway looped about the carriage lengthwise thereof with the carriage resting on the under reach of the chain, so that the chain may move the carriage, a sprocket wheel on the truck meshing with the chain, means for rotating such sprocket wheel to cause the chain to travel and thereby move the carriage if it is free to move, and means for connecting the chain with the container.

4. The combination of a vehicle, a carriage shiftably mounted thereon, an endless chain mounted about sprockets on the carriage adjacent the opposite ends thereof, a sprocket wheel on the vehicle for driving the chain, the carriage resting on the chain between the ends of the carriage and said sprocket wheel, and a reversible motor and reduction gearing for rotating the sprocket wheel.

5. The combination of a vehicle, a carriage movably mounted thereon, means for limiting the movement of the carriage away from the ve-

hicle, an endless chain on the carriage looping around supports adjacent each end of the carriage, means for so connecting the chain to the carriage that the chain may move the carriage, a sprocket on the vehicle intermediately engaging the chain, and a push-and-pull bar adapted to connect the chain with the container to be moved.

6. The combination of a vehicle, a transverse guideway thereon, a carriage movably mounted in the guideway to project beyond either side of the vehicle, said carriage having wheels adjacent its ends and abutment faces beyond the wheels, an endless chain looped around such wheels and having an upper and a lower reach, a sprocket wheel on the vehicle which is engaged by the lower reach of the chain, a second vehicle alongside of the vehicle described and at such relative elevation that the end of the projected carriage abuts the side of the said second vehicle, a bridge connecting the two vehicles and limiting their approach and separation, means to connect the upper reach of the chain with a demountable body which may ride on either vehicle, and means for operating said sprocket wheel on the vehicle in either direction.

7. The combination of a vehicle, a pair of guideways thereon, a pair of carriages movably mounted in the guideways, a pair of endless chains mounted respectively on the carriages on supports adjacent the ends thereof, there being such connection between the carriage and chain that the chain may move the carriage, the lower reaches of said chains passing into engagement with sprocket wheels on the vehicle, a driving shaft for operating the two sprocket wheels on the vehicle and a reversible motor for operating the shaft.

8. In a transfer system of the character described, the combination of a vehicle, a carriage bodily shiftable on the vehicle, an endless chain on the carriage, means on the vehicle for moving the chain, means by which the movement of the chain may move the carriage, means for attaching a container to the chain, and means for attaching the chain to the carriage.

9. The combination of a vehicle, a carriage movably mounted thereon, an endless chain mounted on the carriage, a sprocket on the vehicle which the chain engages, a reversible motor for rotating the sprocket, and a push-and-pull bar removably connected at one end thereof to a container and provided at the other end with means for attachment to the chain and means for attachment to the carriage, whereby the container may be attached to the chain or to the carriage for movement by either of them.

10. The combination of a highway vehicle, a transverse guideway thereon, a carriage mounted in the guideway adapted to move to either side of the vehicle, an endless chain on said carriage passing around wheels on the carriage adjacent the ends thereof, means for supporting the upper reach of the chain between the wheels, a sprocket carried by the vehicle in engagement with which the lower reach of the chain extends, means for rotating said sprocket in either direction, stops to limit the movement of the carriage in either direction, and means for attaching the chain to a demountable container and for attaching the chain to the carriage.

11. The combination of a vehicle, a guideway thereon, a shiftable carriage on the guideway, a chain on the carriage, means on the vehicle for operating the chain, a demountable con-

tainer, and a push-and-pull bar adapted to be connected at one end to the container and at the other end having a jaw adapted to engage the chain, said push-and-pull bar having also a connection adapted to engage the carriage, whereby both push-and-pull bar and the chain may be attached to the carriage.

12. The combination of a highway vehicle, with a pair of longitudinal sills, a transverse housing carried on top of the sills, a carriage slidably mounted in the housing, a pair of wheels at the opposite ends of the carriage, an endless sprocket chain lying in a vertical plane extending over the wheels, a supporting bar on the carriage for supporting the upper reach of the chain between the wheels, a driving shaft rotatably carried by the vehicle frame, a sprocket on said shaft engaging the lower reach of the chain, the carriage being free for movement due to a pull by the sprocket on the lower reach of the chain, a reversible motor carried by the vehicle frame and connected with the sprocket, means for attaching the upper reach of the chain to a container to be moved to or from the vehicle, and means for attaching such container to the carriage.

13. The combination of a vehicle, a bodily shiftable carriage thereon, an endless chain on the carriage extending lengthwise thereof and movable relative thereto, means whereby the chain tends to move the carriage when the latter is free for movement, driving means mounted on the vehicle independently of the carriage and engaging the chain, a stop limiting the movement of the carriage, whereby the chain may shift the carriage until the latter encounters the stop and thereafter may move relative to the carriage, and means adapted to connect the chain with a container to be shifted toward or from the vehicle.

14. In a system of transferring freight, the combination of a truck, a carriage shiftably mounted thereon, an endless chain on the carriage, a container adapted to ride on the truck, a push-and-pull bar connecting the chain to the container, means for shifting the carriage and chain relative to the container on the truck, means for shifting the chain, container and connecting push-and-pull bar relative to the carriage and truck and means for shifting the carriage, chain, push-and-pull bar and container as a unit relative to the truck.

15. The combination of a vehicle, a bodily shiftable carriage thereon, an endless chain on the carriage extending lengthwise thereof and movable relative thereto, means whereby the chain tends to move the carriage when the latter is free for movement, driving means mounted on the vehicle independently of the carriage and engaging the chain, a stop limiting the movement of the carriage, whereby the chain may shift the carriage until the latter encounters the stop and thereafter may move relative to the carriage, means adapted to connect the chain with a container to be shifted toward or from the vehicle, and a bridge carried by the vehicle and adapted to be attached to the other member to or from which the container is to be shifted.

16. Container transfer equipment for a vehicle, said equipment comprising: a bodily shiftable carriage on the vehicle and adapted to project from a side thereof, an endless chain on the carriage, a push-pull bar extending lengthwise of said chain and connected at one end to said chain, said bar at the other end thereof

being adapted to extend beyond said chain, carriage and vehicle for connection to a distant container to be transferred to the vehicle, means for driving said chain, and means for transmitting the drive of said chain to said carriage to thereby shift said carriage.

17. The combination of a vehicle, a pair of parallel carriages slidably mounted on the vehicle, an endless chain mounted on each carriage and extending along the carriage parallel with its path of movement, means on the vehicle for propelling the chains, means preventing independent movement of the carriages and chains whereby the chains may move the carriages, and push-and-pull bars extending lengthwise of the chains to connect the chains with a container which may stand beyond the end of the chain.

18. The combination of a vehicle, a transverse guideway thereon, a carriage slidably mounted in the guideway to move to the side of the vehicle, an endless chain on the carriage, a driving sprocket on the vehicle engaging the chain, means for anchoring the chain to the carriage whereby the sprocket may move the chain and carriage as a unit, said carriage being formed at its end with a flat head to abut the side of a railway car, a demountable body adapted to be received on the railway car and means for connecting said body to the chain.

19. The combination of a vehicle having a guideway, a carriage movably mounted in the guideway, a chain on the carriage, means for anchoring the chain to the carriage, and a sprocket wheel on the vehicle for operating the chain and by the chain operating the carriage, said carriage being provided at its end with cushioning means to abut the side of a railway car.

20. The combination of a vehicle, a shiftable carriage thereon, means for moving the carriage, a movable chain on the carriage, a push-and-pull bar provided with means for engaging the chain, and an anchor carried by the push-and-pull bar adapted to engage the carriage.

21. In a freight transferring mechanism, the combination of a vehicle, a bodily movable carriage thereon, an endless chain looped about the carriage, means on the vehicle for driving the chain, a push-and-pull bar adapted to connect the chain with a container, and an anchor connected to the push-and-pull bar, said anchor being adapted to engage the carriage for connecting the push-and-pull bar thereto.

22. The combination of a vehicle, a shiftable carriage thereon, an endless chain extending lengthwise of the carriage and looped about supports at each end thereof, a push-and-pull bar having a jaw adapted to connect with the chain, and an anchor pivoted to the push-and-pull bar and adapted to engage the carriage.

23. A system of transferring freight comprising a vehicle, a bodily shiftable carriage thereon, an endless chain on the carriage, means on the vehicle for operating the chain, means for causing the carriage to rest on the chain in a region where the chain is supported whereby the movement of the chain may shift the carriage and means for connecting the chain to a container to be shifted, whether the container is over the chain or distant therefrom.

24. A system of transferring freight comprising a highway vehicle, a carriage thereon, an endless chain looped around the carriage, a container adapted to rest on the vehicle, means for driving the chain and thereby shifting the car-

riage and chain relative to the vehicle and container, means for attaching the container to the chain, means for preventing movement of the carriage whereby said driving means may shift the chain and container relative to the vehicle and carriage, and means for attaching the container to both the chain and carriage whereby said driving means may shift the carriage, chain and container as a unit relative to the vehicle.

25. A frame slidably mounted on a vehicle, 10 sprockets rotatably mounted on said frame near the ends thereof, an endless chain running over said sprockets, a bar arranged to be connected at one end to a container on the vehicle, a dog on the other end of the bar arranged to be connected to the chain, means for driving the chain to move the container through the bar relative to the frame, and a member on the frame arranged to be engaged by a member on the chain to cause the frame to move with the chain.

26. A frame slidably mounted on a vehicle, sprockets rotatably mounted on said frame near the ends thereof, an endless chain running over said sprockets, a bar arranged to be connected at one end to a container on the vehicle, a dog on the other end of the bar arranged to be connected to the chain, and means for driving the chain to move the container through the bar relative to the frame, said dog being arranged to cause the frame to move with the chain.

27. A frame slidably mounted on a vehicle, sprockets rotatably mounted on said frame near the ends thereof, an endless chain running over said sprockets, a bar arranged to be connected at one end to a container on the vehicle, a dog on the other end of the bar arranged to be connected to the chain, means on the vehicle for driving the chain to move the container through the bar relative to the frame, and a member on the frame arranged to be engaged by said dog to cause the frame to move with the chain.

28. The combination with a vehicle of equipment for transferring freight containers to and from the vehicle, said equipment comprising an arm, guiding means on the vehicle for slidably receiving said arm, a chain for driving said arm along said guiding means in a substantially rectilinear, longitudinal movement between a posi-

tion in which one end of said arm extends outwardly from one side of said vehicle and a position in which the other end of said arm extends outwardly from the opposite side of said vehicle, and a bar adapted at one end for detachable connection with said arm adjacent either end thereof, said bar being adapted at the other end thereof for detachable connection with a freight container.

29. Container transfer equipment adapted for mounting on a vehicle for transferring a container to or from the vehicle and from either of two opposite sides of the vehicle, said equipment comprising: an arm slidably mounted on the 15 vehicle for longitudinal, rectilinear movement into and between outwardly projecting positions at opposite sides of the vehicle, a push-pull bar extending longitudinally of said arm and adapted at the outer end thereof for connection to a container to be transferred relative to the vehicle, and a chain adapted to drive the inner end of said bar from adjacent one end to adjacent the other end of said arm and to drive both said arm and said bar with said inner bar end positioned adjacent either end of said arm.

30. Container transfer equipment adapted to be mounted on a vehicle for transferring a container to or from the vehicle and from either of two opposite sides of the vehicle, said equipment

35 comprising: an arm member slidably mounted on the vehicle for longitudinal, rectilinear movement into and between outwardly projecting positions at opposite sides of the vehicle, a push-pull bar member extending longitudinally of said arm and adapted at the outer end thereof to be detachably secured to a container to be transferred relative to the vehicle, means providing disengageable driving connection for the inner end of said bar member with said arm member adjacent either end thereof, and a chain adapted to engage one of said members and drive said arm member, said bar member, and said container relative to the vehicle with said inner bar end connected to said arm member adjacent 40 either end thereof.
